UNITED STATES PATENT OFFICE.

HARVEY C. MUMMERT, OF HOLLIS, AND WILLIAM WAIT, JR., OF GARDEN CITY, NEW YORK, ASSIGNEES, BY MESNE ASSIGNMENTS, TO CURTISS AEROPLANE AND MOTOR COMPANY, INC., OF GARDEN CITY, LONG ISLAND, NEW YORK, A CORPORATION OF NEW YORK.

METHOD OF CONSTRUCTING RADIATORS FOR USE IN CONNECTION WITH INTERNAL-COMBUSTION MOTORS.

Application filed October 26, 1922. Serial No. 597,072.

To all whom it may concern:

Be it known that we, HARVEY C. MUMMERT and WILLIAM WAIT, Jr., citizens of the United States, residing, respectively, at Hollis, county of Queens, and Garden City, county of Nassau, and State of New York, have invented certain new and useful Improvements in Methods of Constructing Radiators for use in Connection with Internal-Combustion Motors, of which the following is a specification.

Our invention relates to radiators for internal combustion motors, and especially the internal combustion motors of aeroplanes or other aerial craft, and is concerned merely with the method of constructing such radiators as distinguished from the article itself.

The particular type of radiator with which the present invention is concerned is that type known in the art as the "skin or surface" type radiator; i. e., a radiator comprising a series of cells or water passages arranged side by side and preferably parallel to provide when grouped together an outer skin or covering for one or more of the principal flight resisting masses of the aeroplane or other aerial craft.

Radiators thus characterized are preferably constructed of superimposed metal plates fastened together to admit of the circulation of a cooling agent therebetween, the plates throughout their full surface area being approximately divided to provide the desired number of cooling cells. The method of constructing them consists in applying a coating of solder solution upon one of said plates, in superimposing upon the coated surface of said first mentioned plate the other of said plates, said second mentioned plate being a corrugated plate and having its corrugations preferably parallel, and finally in sufficiently heating the superimposed plates by applying the heat upon the exterior surface of one of said plates to effect a solder-joint therebetween. To take care of expansion and contraction due to temperature changes, the first mentioned plate is also slightly corrugated, the corrugations being relatively shallow and so disposed with respect to the corrugations in the other of said plates as to enter or extend thereinto; the solder-joint being relied upon

to completely separate the water passages or cells and at the same time to reenforce the radiator throughout.

Skin or surface type radiators thus constructed are extremely efficient, due to a total absence of head resistance, are comparatively inexpensive of manufacture, and can be varied in size indefinitely by simply enlarging the plates and multiplying the number of water passages or cells.

Other advantages resulting from the methods employed will be hereinafter pointed out.

In the drawings, wherein like reference characters denote like or corresponding parts:—

Figure 1 is a plan view of an aeroplane supporting surface or wing showing the manner in which a radiator constructed in accordance with the methods herein disclosed is fastened in place;

Figure 2 is an enlarged detail sectional view taken on the line 2—2 of Figure 1;

Figure 3 is a similar view taken on the line 3—3 of Figure 1;

Figure 4 is an end elevation of the device or apparatus used in the manufacture of such radiators to heat the plates and at the same time exert the necessary pressure upon the coated portions thereof to effect the desired solder-joint;

Figure 5 is a transverse section of the device or apparatus illustrated in Figure 4;

Figure 6 is a plan view of a portion of the bed employed in the manufacturing process;

Figure 7 is a transverse sectional view of that portion of the bed illustrated in Figure 6;

Figures 8 and 9 are enlarged sectional views showing the manner in which the rolling device or apparatus of Figures 4 and 5 is adapted to cooperate with the bed of Figures 6 and 7 to produce the corrugations in one of the radiator plates and at the same time effect the desired solder-joint between the radiator plates when superimposed;

Figure 10 is a similar view further illustrating the manufacturing process;

Figure 11 is a similar view showing the manner in which the plate ends are overlapped;

Figure 12 is a plan view, partly broken away, of one of the radiator sections, the

same having been manufactured by the methods herein explained; and,

Figure 13 is a detail sectional view illustrating the manner in which adjacent radiator sections are fastened together.

In the embodiment of the invention selected for illustration a wing type radiator, designated in its entirety as 20, is shown. Said radiator comprises a plurality of radiator sections 21, each of which sections is an exact duplicate of the other. By varying the number of sections, the size of the radiator may be varied, since the number of radiator sections required depends upon 10 the power output of the motor in connection with which the radiator is used.

In its manufacture, the sections 21 of the radiator 20 are separately produced and thereafter fastened together edge to edge in 20 the manner shown. When thus assembled, the radiator in its entirety is slipped over the wing or other part of the aeroplane which provides its support.

In the manufacture of the radiator sections a bed-plate 22 is provided, the size 25 of the bed-plate being directly proportioned to the size of the radiator sections desired to be made. On the top face of the bed-plate 22 a series of metal rods 23 are disposed, the rods in each instance being of 30 circular section and parallel. That face of the bed-plate having the rods 23 extended there-across constitutes its working face. Upon the working face of the bed-plate a 35 flat metal plate 24 is laid. Said plate 24 is slightly corrugated as at 25 by passing a weighted roller device or apparatus 26 over its top surface, the pressure exerted by the weight of the roller device being relied upon to slightly deform the plate 24 to thereby produce the corrugations. The 40 rollers 27 (of which there are two) of the device or apparatus 26 are corrugated as indicated in Figure 4, the rollers being arranged one behind the other in order that the corrugations of the one roller may follow in the track defined by the corrugations of the other. Preferably, the number of 45 corrugations formed in the rollers 27 is double the number of rods 23 fastened on the working face of the bed-plate 22.

Having corrugated the metal plate 24 in the manner indicated, said plate, which constitutes the bottom plate of the finished 50 radiator section, is coated on its top face or surface with a solder solution which is immediately permitted to cool. Upon the coated face of the plate 24 a second metal plate 26' is superimposed. Said plate 26' 55 is also corrugated, the corrugations 27' of the top plate being somewhat deeper than the corrugations 25 formed in the bottom plate 24. In superimposing the metal plates 24 and 26', care should be taken that the 60 corrugations 27' of the plate 26 span the

corrugations 25 in the plate 24, since it is desirable in the finished product that the shallow corrugations 25 enter every other one of the deeper corrugations 27'. Before placing the plate 26 upon the plate 24, such portions of the plate 26 as bear upon the plate 24 are also coated with a solder solution to the end that a solder-joint 70 between the superimposed plates may be effected by the application of heat and pressure in a manner hereinafter more fully explained.

To effect the desired solder-joint between the superimposed plates the device or apparatus 26 is again rolled along the plates, 80 this time in bearing contact with the top plate 26' in order that the desired pressure may be exerted at the points where the two plates engage. In conjunction with the device or apparatus 26 a heater 27' is employed, the heater (see Figure 4) having a flexible connection 28 with an appropriate source of supply. As the device or apparatus 26 is moved along the top face of the superimposed plates, it is apparent that the 90 desired solder-joint between the plates is effected by the well-known sweating process. With the plates thus joined together, obviously the desired number of water passages or cooling cells are provided, each cell 95 being of a construction such that expansion and contraction, within certain limits, due to temperature changes, may take place without disrupting the solder-joint. With the plates thus joined, that portion of each plate 24 extending beyond the ends or edges of the plate 26' is folded over and upon the top face of the plate 26' (see Figure 11) where it is soldered in place, the space indicated at 28' on the under-side of the device or apparatus 26 being provided for this 100 purpose.

After producing the desired number of radiator sections the several sections are placed edge to edge with their flattened portions in over-lapping contact and riveted together by the use of eyelets 29. In this manner a radiator of the size desired is built up in the form of a hollow shell, the hollow of which, in transverse section, is preferably substantially complementary to that portion of the aeroplane (the aeroplane wing of Figure 1) which is utilized as the 110 radiator support.

It should be noted further that the ends of the plates 24 and 26', as well as the edges, do not terminate flush with each other, but that the ends of the top plate 26' extend beyond the corresponding ends of the bottom plate 24. Over the projecting ends of the top plate 26' end plates 30, of channel section, are fastened, said plates, together with inner end plates 31, carried by the bottom plates 24, defining headers 32 to which all of the cells or water passages lead. The 120 con-

nection between the end plates 30 and the plates 26' is also effected by a solder-joint.

From the above description, taken in connection with the accompanying drawing, it is apparent that the method of constructing the radiators consists in applying a solder solution upon one surface of a corrugated metal plate (the plate 24) and thereafter permitting the solder solution to cool; in superimposing upon the coated surface of said plate 24 a second corrugated plate 26' having corrugations formed therein of greater depth than the corrugations formed in the plate 24, said corrugated plates being so disposed one upon the other as to cause the relatively shallow corrugations 25 formed in one of said plates to enter the relatively deeper corrugations 27' formed in the other of said plates, said plates, thus positioned, jointly defining the series of water passages or cells; and finally, in effecting a solder-joint between the superimposed plates by the exterior application of heat and pressure upon such portions of the plates as bear directly one against the other, the solder-joint thus obtained being relied upon to close communication between adjacent water passages or cells.

While we have described our invention in detail in its present preferred embodiment, it will be obvious to those skilled in the art after understanding our invention, that various changes and modifications may be made therein without departing from the spirit or scope thereof. We aim in the appended claims to cover all such modifications and changes.

What we claim is:

1. The method of constructing skin or surface type radiators for aeroplanes which consists in applying a coating of solder solution upon at least a portion of one surface of a metal plate, in laying upon the coated surface of said metal plate a second metal plate, one of said plates being corrugated to provide a plurality of laterally spaced lines of longitudinally continuous contact be-

tween said plates, said lines of contact being spaced according to the size of the mentioned corrugations, and in simultaneously heating and pressing together, along said lines of continuous contact, the mentioned plates, to effect, along said lines of contact, a series of longitudinally continuous laterally spaced solder joints between said plates, 55 said plates, when thus joined together, defining a plurality of independently water tight and completely separated fluid passages or cells.

2. The method of constructing skin or surface type radiators for aeroplanes which consists in forming, by any suitable means, a series of corrugations in a thin metal plate, in applying a coating of solder solution upon at least a portion of one surface of said corrugated metal plate, in laying upon the coated surface of said corrugated metal plate a second metal plate, said second mentioned metal plate having formed therein a series of corrugations deeper than the 70 corrugations formed in said first mentioned plate, said second mentioned plate being so laid upon said first mentioned plate as to cause the corrugations of the former to enter into certain of the deeper corrugations 75 of said last mentioned plate, such superimposition of said metal plates effecting a plurality of laterally spaced lines of longitudinally continuous contact between said plates, and in simultaneously heating and pressing 80 together, along said spaced lines of continuous contact, the mentioned plates, the application of heat and pressure being relied upon to effect a series of longitudinally continuous soldered joints along said spaced lines of 85 contact between said plates, said plates, thus joined together, defining a plurality of independently water tight and completely separated fluid passages or cells.

In testimony whereof we hereunto affix 90 our signatures.

HARVEY C. MUMMERT.
